UNITED STATES PATENT OFFICE.

JOHN J. FEELEY, OF MANTON, RHODE ISLAND.

BRAIDING-MACHINE.

SPECIFICATION forming part of Letters Patent No. 727,926, dated May 12, 1903.

Application filed February 24, 1903. Serial No. 144,769. (No model.)

To all whom it may concern:

Be it known that I, JOHN J. FEELEY, a citizen of the United States, residing at Manton, in the county of Providence and State of Rhode Island, have invented a new and useful Improvement in Braiding-Machines, of which the following is a specification.

This invention has reference to an improvement in braiding-machines, and more particularly to an improvement in the thread tension and delivery mechanism on the movable racers of braiding-machines.

In movable racers for braiding-machines as heretofore constructed the tension-weight sliding on its support abuts directly against the lower end of the latch. The latch sliding on the same support above the tension-weight has an arm extending over the bobbin to engage with teeth on the head of the bobbin, and the upper end of the support is contracted to allow the removal of the latch and tension-weight. The draft of the thread on the tension-weight lifts the weight and latch. The draft of the thread may lift the latch beyond its normal operative position and into the contracted portion of the support. The latch, being lifted from its lower end and overbalanced by the weight of its outwardly-extending arm, fails to engage with a stop on the upper end of the support and falls outward from the contracted portion of the support, preventing the proper operation of the tension and delivery mechanism.

The object of my invention is to so lift the latch that when carried upward and out of its normal operative position it will engage with the stop on the support and when released will drop back into its normal position.

My invention consists in the peculiar and novel construction of the tension-weight having an upwardly-extending arm engaging with the latch-arm to lift the latch at a point that will prevent overbalancing of the latch, as will be more fully set forth hereinafter.

Figure 1 is a side view of a movable racer for braiding-machines, showing my improved tension-weight with its upwardly-extending arm in engagement with the latch-arm at a point to prevent overbalancing of the latch. Fig. 2 is an enlarged detail view of the thread tension and delivery mechanism looking from the bobbin side of the mechanism, with its

support broken away from the frame of the racer, and showing my improved tension-weight in its operative position with the latch-arm. Fig. 3 is a sectional view taken lengthwise through Fig. 2. Fig. 4 is a transverse sectional view taken on line X X of Fig. 2, showing the latch and its support; and Fig. 5 is a transverse sectional view taken on line Y Y of Fig. 2, showing the means of holding the tension-weight on its support.

In the drawings, *a* represents a bobbin having the teeth *a'* *a''* (usually six in number) on its upper or head end. The bobbin *a* is placed on a vertical spindle projecting upward from the frame *b*. Extending upward from the frame *b* is the support *b'* for the thread tension and delivery mechanism. The support *b'* forms a guide for the tension-weight *c* and the latch *d* and has the contracted portion *b*² on its upper end, the stop *b*³, and the guide-eyes *b*⁴ and *b*⁵ for the thread. The tension-weight *c*, sliding on the support *b'*, has the lips *c'* *c''* shaped to loosely fit the support and form the elongated openings *c*² *c*³ slightly wider than the contracted portion *b*² of the support. On the outer lower edge of the tension-weight *c* is the slot *c*³, forming a guide for the thread, and on the inner side is the upwardly-extending arm *c*⁴ to engage with the latch-arm. The latch *d*, sliding on the support *b'* above the tension-weight, has the lips *d'* *d''*, loosely fitting the support and forming the elongated opening *d*², slightly wider than the contracted portion *b*² of the support, and the arm *d*³, extending outward and over the upwardly-extending arm *c*⁴ on the tension-weight and engaging with the teeth *a'* *a''* on the bobbin.

In the operation of the thread tension and delivery mechanism with my improved tension-weight the thread coming from the bobbin passes through the guide-eye *b*⁴ in the support, then downward and through the slot *c*³ in the tension-weight, then upward and through the guide-eye *b*⁵ in the support to the point where the several threads in the machine are braided together. The draft of the thread as it comes from the bobbin raises the tension-weight *c*. This in turn, through the upwardly-extending arm *c*⁴ engaging with the arm *d*³ on the latch *d*, raises the latch, with the arm *d*³, from the teeth *a'* on the bobbin, allowing the bobbin to revolve one tooth.

The latch now falls by gravity and catches the next tooth on the bobbin. This operation is repeated indefinitely, delivering a predetermined amount of thread for each upward movement of the latch. If the latch *d* should be carried upward and out of its normal operative position, the arm *c*⁴ on my improved tension-weight engaging with the arm *d*³ on the latch would prevent the latch from overbalancing and falling out and cause it to engage with the stop *b*³ on the support *b*', when it would drop back into its normal position on the support *b*' by gravity.

Having thus described my invention, I claim as new and desire to secure by Letters Patent—

1. In a movable racer for braiding-machines, a frame having a spindle and bobbin, a support on the frame, a sliding tension-weight on the support, a sliding latch on the support with an outwardly-extending arm to engage with teeth on the bobbin, and means on the tension-weight to engage with the latch at a point to prevent overbalancing of the latch by the weight of the latch-arm, when the latch

is raised out of its normal operative position by the draft of the thread on the tension-weight, as described.

2. In a movable racer for braiding-machines, the combination with the bobbin *a* having the teeth *a*' *a*'', the frame *b* having a spindle for the bobbin, and the support *b*' with the contracted portion *b*², the stop *b*³, and the guide-eyes *b*⁴ and *b*⁵, the tension-weight *c* with the lips *c*' *c*' forming the elongated openings *c*² *c*³, the slot *c*³, and the upwardly-extending arm *c*⁴, the latch *d* having the lips *d*' *d*' forming the elongated opening *d*², and the arm *d*³ extending outward and over the upwardly-extending arm *c*⁴ on the tension-weight and engaging with the teeth on the bobbin, all for the purpose as described.

In testimony whereof I have signed my name to this specification in the presence of two subscribing witnesses.

JOHN J. FEELEY.
